[57] CLAIM

The ornamental design for a wall mounted holder for stuffed toy animals, substantially as shown and described.

DESCRIPTION

FIG. 1 is a front elevational view of a wall mounted holder for stuffed toy animals showing my new design: it being understood that the broken lines showing of the stuffed animals is for illustrative purposes only;

FIG. 2 is a side elevational view;

FIG. 3 is a sectional view taken along line 3—3 of FIG. 1;

FIG. 4 is a rear elevational view;

FIG. 5 is a top plan view;

FIG. 6 is a bottom plan view; and

FIG. 7 is a front elevational view of a modified form of the wall mounted holder for stuffed toy animals shown in FIG. 1.
